UNITED STATES PATENT OFFICE.

VAN AUSTIN TARBLE, OF MARTINSVILLE, ILLINOIS.

WRENCH.

1,333,002.

Specification of Letters Patent.

Patented Mar. 9, 1920.

Application filed October 29, 1917. Serial No. 199,169.

To all whom it may concern:

Be it known that I, VAN AUSTIN TARBLE, a citizen of the United States, residing at Martinsville, county of Clark, State of Illinois, have invented certain new and useful Improvements in Wrenches, of which the following is a specification.

The present invention relates to tools and particularly to that type known as wrenches.

An object of the present invention is to provide an improved structure of tool embodying the characteristics of a nut and pipe wrench, the said tool comprising a threaded stem having a recessed shank positioned thereabout which carries the rigid jaw at its end, and a movable jaw slidable over the rigid jaw carrying shell and provided with a rim projecting into a longitudinal slot formed in the shell, which rim has teeth upon its inner edge for meshing engagement upon the stem whereby the movable jaw may be moved toward or away from the rigid jaw by rotation of the stem, and also to provide a spring latch for engagement in a notch formed in the stem of the rim structure.

The invention further aims at the provision of a tool embodying these features and which comprises relatively few parts, simply and easily adjusted and assembled, and a tool which may be economically manufactured and which is most efficient in its purpose.

The above and various other objects and advantages of this invention will be in part described and in part understood from the following detailed description of the present preferred embodiment, the same being illustrated in the accompanying drawing, wherein:

Figure 1 is a longitudinal section through a tool constructed according to the present invention.

Fig. 2 is a transverse section through the tool taken on the plane indicated by the line 2-2 in Fig. 1.

Fig. 3 is a similar section taken on the plane indicated by the line 3-3 in Fig. 3 through the shank of the tool.

Fig. 4 is a detailed perspective view of a portion of a threaded stem, showing the releasing and connecting grooves or recesses.

Referring to this drawing, 10 designates the stem of the tool which is preferably made in one piece and extends from end to end thereof. The stem has a head 11 upon

one end which may be termed the outer end of the tool, and against which fits a fixed jaw 12. The jaw 12 surrounds the stem, has a counter-sink in its outer end receiving the inner side of the head 11 therein, and is provided upon its inner face with teeth or serrations 13 adapted to grip the exterior surface of a pipe or other cylindrical object with which the wrench of this invention may be engaged. The fixed jaw 12 is provided with a preferably integral shank 14 which is non-circular in cross-section and which extends longitudinally of the stem 10, has a relatively deep recess 15 in one side receiving the stem 10 therein for inclosing and protecting the latter, and fits at its inner end in a socket 16 which also surrounds the stem and has a corresponding non-circular opening therein adapted to inter-lock with the shank 14.

Upon the shank is slidably disposed a movable jaw 17 which has an outer surface arranged substantially in parallelism with the inner face of the fixed jaw 12, and which is provided internally with a longitudinally extending rib 18 fitting in the open side of the recess 15 and terminating in proximity to the stem 10. The rib 18 is provided with relatively cross transversely extending fragmentary screw threads adapted to mesh with correspondingly formed screw threads 19 on the stem 10, the threads 19 being interrupted at one side of the stem and forming a longitudinal groove 20 at said side of the stem through which the threaded rib 18 is adapted to mesh. The jaw 17 may thus be slid longitudinally upon the shank 14 within the range of the tool, and upon rotation of the stem 10 the threads 19 thereof are turned and not only brought into intermeshing engagement with the rib 18, but also bind against the rib and advance the movable jaw 17 against the object to be gripped.

The socket 16 has an aperture through its inner end forming a journal for the stem 10, and the stem 10 inwardly of the socket has exterior screw threads 21 over which is threaded a hand grip 22 of wood or the like which is locked on the stem, and is reinforced by ferrules 23 also threaded on the stem and engaged at opposite ends of the grip 22. The inner faces of the ferrules 23 are recessed and the ends of the hand grip have bosses thereon fitting in the recesses of the ferrules to provide relatively large fric-

tional contact surfaces between the hand grip and the ferrules for inter-locking the parts, and also for the purpose of preventing the slipping of the hand grip 22. By 5 turning the hand grip 22 the stem 10 may be rotated in either direction.

The socket 16 is provided at one side and within its outer end with a tension spring 24 of preferably the leaf type which is secured at one end by screw 25 to the inner wall of the socket 16 near the outer extremity of the latter. The free inner end of the spring 24 is provided with a bearing block 26 adapted to seat in a transverse notch 27 10 formed in the stem 10 in longitudinal alignment with the groove 20 therein. The notch 27 is spaced inwardly from the groove 20 and forms no part thereof, and has an inner 15 relatively flat transverse face against which the block 26 engages. The tension of spring 24 may be varied by tension screw 28 which is threaded through the adjacent side of the socket 16 and bears at its inner end against the spring 24. The tension spring with its 20 block comprises a tension means for indicating the adjustment of the groove 20 in register with the rib 18 of the movable jaw as when turning the handle 23 relatively to the shank 14 and the socket 16 the block 26 offers 25 the greatest resistance to the turning of the stem and handle when the block lies flat upon the inner wall of the notch 27.

The fixed jaw 12 is provided at one side with a notched hammer head 29 which preferably has a milled or corrugated surface used for impact against nails and other objects when using the tool as a hammer. The movable jaw 17 may be adjusted longitudinally toward and from the fixed jaw 12 to 40 add or detract weight with respect thereto for varying the desired impact of the hammer head 29 upon objects to be struck.

The use of the tool is apparent for, aside from its use as a hammer, as above stated, the jaws 12 and 17 may be adjusted against the opposite sides of a nut or pipe by bringing the groove 20 of the stem into register with the rib 18 and manually sliding the jaw 17 into contact with the adjacent side 45 of the object to be gripped. The handle 22

is now turned relatively to the shank 14, the stem 10 rotating therewith and bringing the screw threads 19 into meshing engagement with the threads of the rib 18. As shown to advantage in Fig. 4 the interrupted ends 55 of the threads 19 are beveled or tapered to provide wedge or pointed ends to the threads for facilitating the introduction of the threads 19 into the threads of the rib 18. The threads 19 by their inclination to the axis of the stem 10 wedge the movable jaw 17 into binding engagement with the object between the jaws. The wrench may now be turned as a whole to rotate the head or object in the desired direction. To release the 60 object from the jaws it is only necessary to turn the handle 22 in a reverse direction to register the longitudinal groove 20 of the stem with the rib 18, such position being determined by the relaxing of the tension of 65 the spring 24 against the stem.

It is of course understood that various changes and modifications may be made in the details of construction of this invention without departing from the spirit thereof, 75 such changes and modifications being restricted only by the scope of the following claim:

I claim:

In a wrench, the combination of a shank 80 having a fixed jaw on its outer end and a longitudinal slot in its side, a threaded stem revolubly carried within said shank and having a longitudinal slot in its side interrupting the threads, said slots of said shank and 85 stem adapted to be aligned, and said stem provided with a transverse notch in the same longitudinal plane as said slot thereof, a movable jaw slidable on said shank and having a threaded rib projecting through the 90 slot thereof and adapted to engage in the slot and the threads of said stem, a ferrule carried by said shank, a leaf spring connected within said ferrule, a bearing block carried by the free end of said leaf spring 95 adapted to seat in said transverse notch in said stem, and a screw threaded through the adjacent side of said ferrule for varying the tensioning of said spring.

VAN AUSTIN TARBLE.
